UNITED STATES PATENT OFFICE

LEO J. WAHL, OF STERLING, ILLINOIS, ASSIGNOR TO WAHL CLIPPER CORPORATION, OF STERLING, ILLINOIS, A CORPORATION OF ILLINOIS

CLIPPER BLADE CONTROL

Application filed June 22, 1931. Serial No. 545,964.

My invention relates to clippers and has for its principal object the provision of means for controlling the relative positions of the comb, the cutter, and the clipper frame whereby to improve the flexibility of the clipper with respect to the adjustments for varying the closeness of cut by the clipper.

In using clippers, barbers are faced with the problem of evening out the changes in length of the hair between that cut with a fine or close cutting clipper and that cut with a coarse clipper, as well as the change from the clipper to the shears. Various means have been adopted to make a single clipper operate to cut both fine and coarse and gradually change from one to the other, and it is with this line of development that my invention particularly concerns itself.

One purpose of the invention is to provide a novel means of varying the relative relation of comb and cutter to change the closeness with which the clipper will cut the hair.

It is also a purpose of this invention to provide a novel operating device for adjusting the comb and cutter of a clipper which makes it possible to readily adjust the length of cut of the clipper without loosening or changing the hand grip thereon.

Another and more specific object of the invention is to provide a novel mounting whereby the comb is mounted to swing with respect to the frame, and the cutter blade is so mounted as to follow the angular position of the comb with respect to the frame without seriously changing the normal pressure between the cutter and comb.

Other and more specific objects of the invention will appear as the description proceeds in connection with the accompanying drawing wherein the preferred form of the invention is shown.

In the drawing—

Fig. 1 is a side view of a clipper embodying my invention;

Fig. 2 is a top view of the clipper showing the relative position of the operating means;

Fig. 3 is a longitudinal section of a portion of the clipper;

Fig. 4 is a section substantially on the line 4—4 of Fig. 3; and

Fig. 5 is a side view partly in section of a slight modification.

Referring now in detail to the drawing, the clipper body or frame is indicated by the numeral 6. The comb is shown at 7, and the cutter blade at 8. This particular clipper is of the electromagnetic type having an armature 9 and an electromagnet 10 of a well known type by means of which the armature 9 is vibrated to move the cutter blade by means of the connecting element 11. The construction is such that armature 9 and element 11 yieldingly press the comb and cutter together. This, however, is a well known construction in this art and may be of any suitable type desired.

My invention concerns itself particularly with the relation between the comb 7, the cutter 8, and their mounting upon the frame 6 together with the means whereby they may be adjusted.

In the form shown in Figs. 1 to 4 which is the preferred form, the comb is mounted upon a U-shaped member 12, the upstanding legs 13 and 14 of which are pivoted as by means of the screws 15 and 16 to the frame 6. Suitable set screws such as indicated at 17 serve to lock the screws 15 and 16 in position so that they may serve as pivots on which the U-shaped members 12 can swing. As shown, the cutter blade 8 is slotted at 18 to receive the rounded end of the member 11 so that this cutter blade can swing around this rounded end and thus follow the angular position of the comb 7 when it is being adjusted. Comb 7, however, moves about a much longer radius than the cutter 8 so that in changing their positions from that shown in Fig. 1, for example, to that shown in Fig. 3, a relative sliding movement will be caused between them to advance the comb teeth beyond those of the cutter. Naturally there is some change in the position of the cutter with respect to its driving member 11, but the yielding pressure between these two elements permits of this small change without making any appreciable change in the pressure between the comb and cutter.

I find, however, one thing to be highly advantageous in this regard, and that is that

the pivot point for the U-shaped member is placed substantially on a line running perpendicular to the center of the opening 18 when the cutter 8 is in substantially the central position of its movement, and in this way the changes in angular position of the comb and cutter make the least changes in the pressure therebetween.

From the above description, it is believed 10 to be clear that by changing the angular position of the comb and cutter with respect to the frame one of them may be made to slide relative to the other and thus vary the coarseness of the cut on account of the shape 15 of the comb blade used which increases fairly rapidly in thickness from the comb points toward the back end.

In order to change the angular position of the comb and cutter with respect to the 20 frame, I have devised a means which is simple and effective for operating without the necessity of loosening the grip upon the clipper.

This means consists of the thumb piece 19 which as shown has a portion 20 extending 25 across the top of a clipper frame and which is secured by means of the screw 15 to the lug 13 of the member 12. A detent at 21 serves to prevent relative angular movement between the thumb piece 19 and the leg 13 so 30 that they must move in unison.

It is believed to be obvious that with the hand grasping the frame 6 in the usual manner of holding these clippers, thumb piece 19 may be readily depressed or elevated with the 35 thumb without the necessity of releasing the grip upon the clipper.

In Fig. 5, I have shown the member 19 as adapted to a slightly different construction in which the comb 7' is slidable with respect 40 to the frame 6' instead of swingable, and in which the cutter 8', of course, remains fixed with the exception of its transverse movement.

In order to operate this type of adjustable 45 comb, the member 19 fits in a slot 22 in the comb by means of the extension 23 thereof. With this type of construction, it is necessary, of course, that the cutter blade 8 or 8' be cut away back of the teeth to the narrow width 50 as indicated at 24 in Fig. 4 and thus prevent any possibility of the cutter itself striking legs 13 and 14 or the extension 23.

From the above description, it is believed 55 that the construction and advantages of this device will be clear to those skilled in this art. It is also believed to be obvious that various modifications may be made without departing from the scope of the invention as herein set forth.

Having thus described one specific form of my invention, what I claim as new and desire to secure by Letters Patent is:

1. In combination, a clipper frame, a comb, means swingingly mounting said comb on 60 said frame, a cutter blade interposed between

the comb and the frame, and driving means for said blade mounting said blade for angular movement with respect to the frame so that the blade and comb are both angularly movable with respect to the frame, the radius on which the comb swings being materially greater than the radius on which the cutter swings. 70

2. In combination, a clipper frame, a comb, means swingingly mounting said comb on 75 said frame, a cutter blade interposed between the comb and the frame, and driving means for said blade mounting said blade for angular movement with respect to the frame so that the blade and comb are both angularly movable with respect to the frame, the radius on which the comb swings being materially greater than the radius on which the cutter swings, said first named means being pivoted on the forward end of said frame 80 and having an operating portion projecting over the back of the frame. 85

3. In combination, a clipper frame, a comb mounted thereon for angular movement relative to said frame, a cutter blade bearing on 90 said comb and reciprocable to and fro thereon, and driving means for said cutter blade upon which said blade is angularly movable in order to follow the comb, means for moving the comb and cutter blade to change 95 their angular relation to the frame, the mounting of the comb causing it to move farther endwise for a given angular displacement than the cutter blade whereby to cause relative sliding movement between the comb 100 and cutter blade. 100

4. In a hair clipper, a clipper frame, a comb mounted thereon for angular movement relative to said frame, a cutter blade bearing on the comb and reciprocable to and 105 fro thereon, and means mounting said cutter blade for angular movement relative to the frame so that the blade and comb are both angularly movable with respect to the frame, the mounting of the comb causing it to move 110 farther endwise for a given angular displacement than the cutter blade whereby to cause relative sliding movement between the comb and cutter blade. 110

5. In a clipper, a clipper frame, a comb, means pivotally mounting said comb on said frame, a cutter blade cooperating with said comb and reciprocable to and fro thereon, and means pivotally mounting said blade with respect to said frame, the pivotal axis 115 of the blade being between the comb and the pivotal axis of the comb. 120

6. In a clipper, a clipper frame, a comb, means pivotally mounting said comb on said frame, a cutter blade cooperating with said comb and reciprocable to and fro thereon, and driving means for said blade providing a pivotal mounting therefor between the comb and its pivotal axis. 125

7. In a clipper, a clipper frame, a comb, 130

means pivotally mounting said comb on said frame, a cutter blade cooperating with said comb and reciprocable to and fro thereon, and driving means for said blade providing
5 a pivotal mounting therefor between the comb and its pivotal axis, the pivotal axis of the blade and comb being substantially on a line perpendicular to the blade when the blade is in the central position of its
10 movement.

In witness whereof, I hereunto subscribe my name this 12th day of June, A. D. 1931.

LEO J. WAHL.
